[57] **CLAIM**

The ornamental design for a nutcracker, substantially as shown and described.

DESCRIPTION

FIG. 1 is a front perspective view of a nutcracker showing my new design in a closed position;

FIG. 2 is a left side elevational view thereof;

FIG. 3 is a front elevational view thereof;

FIG. 4 is a rear elevational view thereof, with the spiral simulated cord being broken away; and

FIG. 5 is a front perspective view thereof in an opened position.
